UNITED STATES PATENT OFFICE.

FRANK ADAM SILAJ, OF CHICAGO, ILLINOIS.

DESIGN FOR A PEDESTAL FRAME.

Application filed September 15, 1924. Serial No. 10,782. Term of patent 3½ years.

To all whom it may concern:

Be it known that I, FRANK ADAM SILAJ, a subject of the Kingdom of Yugoslavia, residing at 2001 South Loomis Street, in the city of Chicago, county of Cook, and State of Illinois, have invented a new, original, and ornamental Design for a Pedestal Frame, of which the following is a specification, reference being had to the accompanying drawing, forming part thereof.

I claim:

The ornamental design for a pedestal frame as shown.

FRANK ADAM SILAJ.
